TOP ROLL FOR TEXTILE DRAWING MECHANISMS

Richard K. Butler, Whitman, Mass., assignor, by
mesne assignments, to Textile Engineering Cor-
poration, Whitman, Mass., a corporation of
Massachusetts

Application March 23, 1949, Serial No. 82,974

14 Claims. (Cl. 19—142)

1

This application is a continuation in part of my pending application Serial No. 45,045, filed August 19, 1948.

The present invention is an improvement in drawing rolls used for the drafting of textile fibers in the production of sliver, roving, and yarn, and relates particularly to top rolls of the so-called solid type in which the entire roll rotates as a unit, and which conventionally comprise a cast iron or steel body having two integral enlargements or bosses connected by a reduced or neck portion and also having an integral reduced portion projecting from the outer end of each boss forming a gudgeon or journal, the bosses being covered with cots of leather or synthetic or other non-metallic cushioning material having a moderate amount of resilience, which cots ride on the fluted lower rolls which are driven and impart rotation to the top rolls.

To grip and thus draw the strands of sliver or roving between the top and bottom rolls, the top rolls are pulled down against the bottom rolls by weight means applying its pressure to the top rolls through a saddle which bears on the neck of each top roll between the two bosses. To hold the top roll against shifting its position forward or backward, the protruding journals at the ends of each roll are held in slots formed in cap bars located at opposite sides of each roll thus constituting bearings maintaining the top roll in its proper working position.

A well known drawback in the use of these solid top rolls is the friction arising between the rotating surface of the neck of the solid top roll and the coengaging stationary surface of the saddle which bears down on the neck to weight the roll, as well as that arising between the bearing surfaces of the gudgeons and the slots in the cap bars which serve as bearings therefor. These bearing surfaces on the customary roll, being of cast iron or steel, have a relatively rapid rate of wear and become worn to such a degree as to impair their usefulness, with the result that the entire roll must be discarded because incapable of being effectively repaired. While accepted as a necessary incident of established manufacturing procedure, this replacement is still a substantial and continually recurring element of expense in the industry.

To prevent intolerably rapid wear of the necks and gudgeons of the rolls, lubrication must be supplied, but the lubricant used must be applied with the utmost restraint and accuracy to the bearing surfaces alone, both because the oil picks up the ever present lint and fly to collect

2

on the necks and gudgeons, under the saddle, and in the cap bar slots, and also because any spot or film of oil on the cots or on the fibrous material being drafted interferes with the drafting and damages the material. Thus, frequent cleaning of the rolls and saddles, and cleaning of the cap bars, is compelled by the accumulation of lint and fly when oil is used.

It is the object of the present invention to provide a top roll construction in which these objectionable features of operation will be obviated.

To this end, the invention comprises a top roll provided with removable and replaceable elements forming the bearing surfaces, preferably both on the neck and on the gudgeons or journals, and in its preferred embodiment these replaceable elements, or at least their bearing surfaces, are formed of synthetic material characterized by superior frictional characteristics reducing or obviating the necessity for the use of a lubricant therefor. Hence the expenditure of time, effort, and care heretofore required for lubricating the rolls and in cleaning them and their saddles and cap bars from collected fly and lint caught by the lubricant, are avoided or greatly reduced. Further, when damage or wear occurs to impair the bearing surfaces of the rolls, the rolls do not have to be discarded, but are simply supplied with new elements providing the bearing surfaces and thus are restored to full utility in these respects.

An illustrative embodiment of the invention is shown in the accompanying invention in which Fig. 1 is a side elevation of the improved roll. Fig. 2 is a view mainly in axial section of the roll of Fig. 1. Fig. 3 is a section on line 3—3 of Fig. 2, and Fig. 4 a section on line 4—4 of Fig. 2.

Other objects of the invention, and the manner of their attainment, are as made plain hereinafter.

In the preferred embodiment illustrated, the improved roll comprises a shaft 1 having sleeves 3 of metal or other suitable material fitted closely but slidably thereon to form the bosses on which tubular cots 5 of rubber, leather, or other suitable composition are adhesively mounted. As customary, a portion 7 of the exterior of each boss 3 is knurled to provide a better grip for the adhesive employed to cement the cot thereto. To maintain the bosses 3 in proper spaced relation to suit the gage of the particular drawing or roving frame in which these rolls are used, one or more sleeves 9, 11, fitting closely but slidably over shaft 1, are interposed between bosses

3 to maintain the latter in properly spaced relation.

Sleeve 9 located at midlength of the roll is in accordance with the preferred form of the invention formed of material having a coefficient of friction so low that the application of a lubricant thereto is unnecessary or seldom needed. Examples of materials of this class are the high molecular weight synthetic plastic compounds such as the polyamide polymers described in Carrothers Patent No. 2,130,948, of which the material supplied under the name of nylon by E. I. Du Pont de Nemours Co., Wilmington, Delaware, are a related synthetic plastic material supplied by them under the trade name of Teflon, are especially suitable; also the polyvinyl series of resins, ethyl cellulose, cellulose acetate, and others. The sleeve 9 is made of sufficient length to exceed the width of the saddle (not shown) of the weighting mechanism used to weight the top roll, and in the case of narrow gage frames comprises the sole spacing element interposed between and engaged by the two bosses 3. When frames of wider gage are to be equipped with the improved rolls, the sleeves 11 made of metal or other preferred material are employed, of equal length and disposed symmetrically at each side of the synthetic sleeve 9, to hold the bosses 3 further apart, a shaft 1 of appropriate length for the gage of the frame being used in each instance.

To hold the described parts of the roll in place, each extremity of shaft 1 is bored axially and threaded as indicated at 13, and a member 15 preferably of the same or similar synthetic plastic material as the sleeve 9 engaged by the saddle, or of any of the aforesigned plastic materials, is affixed to each end of shaft 1, in axial alignment therewith by means of a screw 17 threaded into the bore 13. This member 15 has a cylindrical portion 19 fitting closely within the bore of the outer end of the proximate boss 3, and a shoulder at the junction of reduced portion 19 with its portion 21 of greater diameter which bears against the end of boss 3 to force the latter inward along shaft 1 when screw 17 is tightened.

As is obvious, the members 15 constitute the gudgeons or journals of the roll, and the cylindrical surfaces 21 form the bearing surfaces engaging the slots of the cap bars (not shown).

To hold the bosses 3 and the bearing sleeve 9 against relative rotation with respect to the shaft 1, the latter is preferably keyed to the interior of each of these elements, herein by making shaft 1 hexagonal, and shaping the interior passage through sleeve 9 and the inward half or two-thirds of the length of the passage through each boss 3 of matching hexagonal shape, such that these parts can slide easily along shaft 1, but cannot rotate thereon, as shown in Fig. 3. The outer one-third or half of the length of the passage in each boss 3 is of circular section, as shown in Fig. 4, thus permitting the journal-forming member 15 and its retaining screw 17 to be rotated as a unit in installing member 15 in the end of the roll; it is preferred to seat the screws 17 in the axial bore and counterbore formed for its reception in member 15 with a press fit, so that these two parts may be handled as a unit in inserting, removing, and replacing.

From the foregoing it will be seen that rolls of various lengths to suit various gages of frames are made up of the same bosses 3, center bearing

sleeves 9, and journal members 15, by merely employing different lengths of shafts 1, and using or omitting the spacer sleeves 11. It will likewise be evident that in the event of injury or wear requiring replacement of any or all of the bearing surfaces on sleeves 9 or journal members 15, these members can be quickly and easily removed by unscrewing one or both of the journal members 15 to release all the parts, followed by replacement of those which need renewal with new members.

The construction prevents all tendency of unscrewing of the journal members 15, which hold the roll assembled in rigid unitary relation, by any fortuitous twisting force tending to revolve one boss with respect to the other or to the shaft 1; but a turn or two of the screws 17 by means of a wrench applied to the sockets in their heads releases all the parts for disassembling by the fingers alone.

The countersinking of the heads of screws 17 flush with the extremities of journal members 15 avoids the creation of projections or angles for the lodgement of lint and fly.

The nature of the preferred materials used to provide the bearing surfaces on the journals and center or saddle bearing makes them capable of running without undue wear in the total absence of applied lubricant, or with unprecedentedly small amounts in cases where abnormal weighting makes lubrication necessary.

While I have illustrated and described a certain form in which the invention may be embodied, I am aware that many modifications may be made therein by any person skilled in the art, without departing from the scope of the invention as expressed in the claims. Therefore, I do not wish to be limited to the particular form shown, or to the details of construction thereof, but

What I do claim is:

1. A top roll for the drawing mechanisms of spinning and roving frames, comprising in combination a roll body including two bosses non-rotatable relative to each other for supporting the customary cots, roll supporting members, and screw means affixing such members non-rotatably to the ends of the roll body.

2. A top roll for the drawing mechanisms of spinning and roving frames, comprising in combination a roll body including two bosses non-rotatable with respect to each other and to the roll body for supporting the customary cots, journal members, and screw means affixing such members to the end portions of such roll body in operatively fixed relation for rotation therewith, and with capacity for removal and replacement when worn.

3. A top roll for the drawing mechanisms of spinning and roving frames, comprising in combination two bosses for supporting the customary cots, a member holding the bosses against relative rotation and in coaxial relation, and means fixed to each end of such member preventing escape of the bosses therefrom and extending beyond the bosses to form pintles supporting the roll in its bearings.

4. A top roll for the drawing mechanisms of spinning and roving frames, comprising in combination two bosses for supporting the customary cots, a member holding the bosses against relative rotation and in coaxial relation, spacing means on such member between the bosses, and gudgeons non-rotatably and releasably secured

to such member holding the bosses against the spacing means.

5. A top roll for the drawing mechanisms of spinning and roving frames, comprising in combination a shaft and bosses thereon, cots on the bosses, spacing means on the shaft holding the bosses apart, and gudgeons non-rotatably fixed on the ends of such shaft and holding the bosses against escape from the shaft.

6. A top roll for the drawing mechanisms of spinning and roving frames, comprising in combination a shaft and bosses thereon, cots on the bosses, spacing means on the shaft holding the bosses apart, and gudgeons non-rotatably fixed on the ends of such shaft holding the parts of the roll in assembled relation.

7. A top roll for the drawing mechanisms of spinning and roving frames, comprising in combination a shaft and bosses thereon, cots on the bosses, spacing means on the shaft holding the bosses apart and having a portion forming a saddle-supporting surface, and gudgeons non-rotatably and releasably secured to the ends of such shaft positioning the bosses and spacing means lengthwise of such shaft.

8. A top roll for the drawing mechanisms of spinning and roving frames, comprising in combination a shaft, two bosses slidably supported on such shaft, cots on the bosses, spacing means slidable on the shaft between the bosses, and gudgeons non-rotatably affixed to the ends of the shaft and cooperating with the spacing means to hold the bosses in operatively fixed positions in the length of the shaft.

9. A top roll for the drawing mechanisms of spinning and roving frames, comprising in combination a shaft, two bosses slidably but non-rotatably supported on such shaft, spacing means on the shaft between the bosses, and means on the ends of the shaft forcing the bosses against the spacing means and extending outwardly beyond the shaft and bosses to form journals for the roll.

10. A top roll for the drawing mechanisms of spinning and roving frames, comprising in combination a shaft, two bosses slidably but non-rotatably supported on such shaft, spacing means on the shaft between the bosses, and gudgeons affixed to the shaft preventing axial movement of the bosses along the shaft.

11. A top roll for the drawing mechanisms of spinning and roving frames, comprising in combination a shaft and a plurality of bosses thereon in mutual splined engagement preventing relative rotation, spacing means mounted on the shaft between bosses in slidable but non-rotatable relation to the shaft, and means in screw engagement with the extremities of the shaft projecting beyond the outer ends of the bosses to form journals for the roll.

12. A top roll for the drawing mechanisms of spinning and roving frames, comprising in combination a shaft polygonal in section throughout at least a portion of its length, a plurality of bosses each having an axial passage shaped to match the polygonal cross-section of the shaft throughout a portion of the length of such passage and a cylindrical shape for another portion of the length of such passage, spacing means on the shaft between the bosses, and gudgeons screwed to the ends of such shaft each having a portion fitting within the cylindrical portion of the passage through a boss.

13. A top roll for the drawing mechanisms of spinning and roving frames, comprising in combination, a shaft of polygonal cross-section, bosses having axial passages conforming throughout a part only of their length to the shape of the shaft slidably but non-rotatably mounted on the shaft, spacing means between the bosses having a saddle-supporting surface of synthetic material, gudgeons extending within non-polygonal portions of the passages through the bosses and projecting beyond the outer ends 25 of the latter and also having bearing surfaces of synthetic material, and screw means affixing the gudgeons to the ends of the shaft.

14. A top roll for the drawing mechanisms of spinning and roving frames, comprising in combination a shaft, a sleeve thereon of synthetic material forming a saddle-supporting surface, spacing elements slidable on such shaft and located at each side of the said sleeve, bosses slidably on the shaft engaging the spacing elements, 30 gudgeons of synthetic material projecting axially from within the bosses, and screw means on the shaft forcing the gudgeons axially against the bosses to urge the latter inwardly against the spacing elements and the spacing elements in 35 40 turn against the sleeve.
